UNITED STATES PATENT OFFICE.

FREDERICK R. SEIDENSTICKER, OF WEST MERIDEN, CONNECTICUT,
ASSIGNOR TO BRADLEY & HUBBARD, OF SAME PLACE.

DESIGN FOR CHANDELIER.

Specification forming part of Design No. 7,575, dated July 21, 1874; application filed June 3, 1874.
[Term of Patent 7 years.]

CASE A.

To all whom it may concern:

Be it known that I, FREDERICK R. SEIDENSTICKER, of West Meriden, in the county of New Haven and State of Connecticut, have invented a new Design for Chandelier; and I do hereby declare the following, when taken in connection with the accompanying illustration and the letters of reference marked thereon, to be a full, clear, and exact description of the same, and which said illustration constitutes part of this specification, and represents a perspective view.

This invention relates to a design for chandelier; and consists in the configuration of the "canopy"—that is, the upper ornament on the pipe or spindle—and of the arms, as shown.

The canopy is of basket-form, consisting of several leaves, rising from a base, and curved outward, meeting near the top, the space between the leaves filled with check-work, as shown. The arms A run up nearly perpendicular from the point of connection B with the body C, and terminate in a right-angular return, D, surmounted by a scroll, E, continued

up and against the pipe, and terminating in a right-angular return, F, like the arms, but reversed. From the body the arms run down, curving outward and upward upon the upper side to the lamp or burner rest G. Upon the under side the arms are a succession of reverse curves H. At the connection with the body a scroll, I, intersects the arm, as shown.

I claim as my invention—

1. The design for chandelier-canopy consisting of several expanding leaves filled between the leaves with check-work, as shown and described.

2. The design for chandelier-arm, consisting of the arm A, curved from the lamp-rest G to the body C, rising therefrom vertically, with the termination D surmounted by a scroll, E, and termination F, the arm ornamented by the scroll I, as described and shown.

FREDERICK R. SEIDENSTICKER.
